UNITED STATES PATENT OFFICE.

JAMES MARTZ, OF WINAMAC, INDIANA.

CAR-COUPING.

SPECIFICATION forming part of Letters Patent No. 240,155, dated April 12, 1881.

Application filed February 1, 1881. (No model.)

To all whom it may concern:

Be it known that I, JAMES MARTZ, a citizen of the United States, residing at Winamac, in the county of Pulaski and State of Indiana, 5 have invented certain new and useful Improvements in Car-Couplers; and I do hereby declare the following to be a full, clear, and exact description of the invention, such as will enable others skilled in the art to which it applies to make and use the same, reference being had to the accompanying drawings, and to the letters or figures of reference marked thereon, which form a part of this specification.

15 My invention relates to a car-coupling or coupling device for railroad-cars; and the novelty consists in the construction and arrangement of parts, as will be more fully hereinafter set forth, and specifically pointed out 20 in the claim.

In carrying out my invention I secure in the adjacent draw-heads or bumpers a coupling-link. One of these links being in each draw-head, it will be understood that they are 25 locked by a gravitational pin coupling together the cars, and that the links and draw-heads are adapted for efficient service in this art by a construction and arrangement which will allow the link of one draw-head, having beveled 30 advancing end, to pass above or below the link in the adjacent draw-head, as will be explained in this specification, and fully shown in the drawings.

It being understood that the coupling-links 35 are in duplicate, and that duplex coupling-links serve as the locking mechanism between the cars, in connection with the gravitational coupling-pins, the details of the invention consist, essentially, in the features and elements hereinafter specified and shown.

In carrying out the invention in detail I employ slotted duplex levers having any convenient or desirable form and adaptation for the service mentioned, said levers being pivoted 45 together, near their inner extremities, each to the truck-head, by a pin or bolt which passes through the slot and is secured to such truck, and one of which carries the coupling-pin. The coupling-pin is hinged or pivoted in such 50 a manner that the coupling-link of one car or truck will recede upon the pressure of the link of the adjacent car, and said pin does not engage the duplex links until such links have been forced past the pivot and the pin gravitates between the links.

It will further be observed that the hanging coupling-pins are automatic couplers, and that the slotted levers serve only as means for uncoupling or elevating the coupling-pins out of locking position with the links.

To enable others to construct and use my invention I will describe it in detail, reference being had to the accompanying drawings, which form a part of this specification, and in which similar letters indicate like parts.

Figure 1 is a side elevation, partially in section; Fig. 2, an end view, showing the levers and gravitational locking-pin; and Fig. 3 is a top plan, and Fig. 4 a detached view, of the pivotal link.

Referring to the drawings, A represents the truck or car body, having wheels *a* and an ordinary draw-head, B, with flaring mouth *b*, and perforation *c* to receive a lock-pin, C, suspended in a vertical position from the pivotal point *d* of levers D, having slots *d'*, and pivoted to the frame by bolts *d''* operating through the said slots *d'*.

E represents the coupling-link, pivoted in the draw-head B, as shown at *e*, and having 80 beveled surfaces *e'*.

The slotted levers D are pivoted together upon their near inner extremities, and approximately near this point is suspended the lock-pin C, which operates in the longitudinal slot 85 *b'* as upon a pivot to lock the adjacent link E' within the draw-head B. The slotted levers D, which support the lock-pin C, are curved laterally in such a manner that the pin C will be afforded a longitudinal oscillatory motion from its pivotal point, operating through the slot *b'*.

I am aware of the construction shown in Patent No. 200,752, and do not broadly claim such device.

What I claim as new, and desire to secure by Letters Patent of the United States, is—

In a car-coupler, the draw-head B, in combination with the link E, pivoted therein, and beveled at *e'*, and the pin C, and levers D, substantially as shown and described.

In testimony whereof I affix my signature in presence of two witnesses.

JAMES MARTZ.
